UNITED STATES PATENT OFFICE.

FRANK A. DELPH, OF NEW ORLEANS, LOUISIANA, ASSIGNOR OF ONE-HALF
TO B. A. COLOMB, OF ST. JAMES PARISH, LOUISIANA.

HEATING APPARATUS.

No. 857,795.

Specification of Letters Patent.

Patented June 25, 1907.

Application filed April 18, 1906. Serial No. 312,396.

To all whom it may concern:

Be it known that I, FRANK A. DELPH, a citizen of the United States, residing at New Orleans, in the parish of Orleans and State of Louisiana, have invented new and useful Improvements in Heating Apparatus, of which the following is a specification.

My invention pertains to heating drums; and it has for its object to provide a heating drum apparatus designed to be used in conjunction with an open fire, and embodying such a construction that perfect combustion of the fuel is assured, and all of the heat values are diverted into an apartment and utilized to heat the same instead of being permitted to escape up the chimney.

Other practical advantages peculiar to my invention will be fully understood from the following description and claims when the same are read in connection with the accompanying drawings, forming part of this specification, in which:

Figure 1 is a vertical section illustrating the apparatus constituting the present and preferred embodiment of my invention as properly arranged relative to an ordinary open fire-place; one of the heating drums being shown partly in side elevation and partly in section. Figs. 2 and 3 are sections taken in the planes indicated by the lines 2—2 and 3—3, respectively, of Fig. 1.

Similar letters designate corresponding parts in all of the views of the drawings, referring to which:

A is an open fire-place having an ordinary or any other suitable basket grate *a* and a flue or chimney *b*. Before my novel apparatus is placed in its working position, the course of the products of combustion from the fire in the grate *a* is directly up the flue or chimney *b*, and after the apparatus is arranged as shown in Fig. 1, relative to the fire-place, the course of the products of combustion is always through the heating drums of the apparatus.

B is the portable apparatus constituting the present and preferred embodiment of my invention. The said apparatus comprises one or more, preferably two, heating drums C, a frame D carrying the said drums and provided with anti-friction rollers E for facilitating the removal of the apparatus from one apartment to another as well as movement of the apparatus toward and from the

fire-place, a plate F fixed with respect to the inner portions of the drums C and designed to close the portion of the fire-place above the grate *a*, a horizontal partition G carried by the plate F and having for its office to prevent direct passage of the products of combustion from the grate to the flue *b* and to compel such products to take passage through the drums C, and a foraminated cover H, preferably of reticulated material as shown, surrounding the drums C and connected to the frame D and plate F, and designed to add stiffness and strength to the apparatus and to prevent persons coming in contact with the drums C as well as to serve as a plate and food warmer and a drier for clothes and other articles.

As best shown in Fig. 2, the drums C are arranged in parallel vertical planes, and each comprises a lower stretch *c* which is preferably, though not essentially, oval in cross-section so as to assure a large pipe-heating surface in proportion to the size or area of the plate F, an upper stretch *d* preferably of the same shape in cross-section as the stretch *c*, and an elbow *e* connecting the outer ends of the stretches *c* and *d* and containing a damper *f* for controlling the passage of products of combustion through the drum. The dampers *f* of the two drums are preferably fixed on a common shaft *g*, Fig. 2, and the elbows *e* are preferably removable from their respective stretches *c* and *d*, this latter to facilitate cleaning of the drums when the same is necessary.

As best shown in Fig. 1, the plate F is provided on its lower portion with a flange F' designed to complete the cut-off and support the inner end of the apparatus on the grate *a*.

It is obvious that in practice the anti-friction rollers E of frame D may be made adjustable vertically with respect to the said frame for different levels; also, that by making the plate F large enough to cover the upper portion of the largest fire-place and equipping it with an adjustable section, the apparatus may be used in combination with different fire-places in different apartments if desired.

In the practical operation of my improvements it will be apparent that the products of combustion from the fire in the grate *a* are caused by the partition G on plate F to pass through the drums C precedent to passing up the flue or chimney *b*, and consequently the

heat of said products is radiated from the drums and used to the best advantage in heating the apartment containing the apparatus.

When it is necessary to supply the fire in the grate *a* with fuel, it is obvious that the same may be conveniently accomplished after my novel apparatus is moved away from the fire-place.

- 10   It will be gathered from the foregoing that my novel apparatus is light in weight and readily portable; also, that when the apparatus is employed the combustion in the grate is complete, it is not necessary to disturb the fire in order to keep the same active, and the fuel is completely reduced to ashes without the loss of particles which renders it feasible to employ a grate having very small openings and in that way reduce waste to a minimum.
- 15   I have entered into a detailed description of the construction and relative arrangement of the parts embraced in the present and preferred embodiment of my invention in order to impart a definite understanding of the
- 20   said embodiment. I do not desire, however, to be understood as confining myself to the
- 25

said specific construction and relative arrangement of parts as such changes or modifications may be made in practice as fairly fall within the scope of my claimed invention. ³⁰

Having described my invention, what I claim and desire to secure by Letters-Patent, is:

A portable heating drum apparatus comprising a supporting frame, a plate carrying a ³⁵ horizontal partition, and one or more heating drums or conduits carried by the frame and plate and having lower and upper stretches open at their inner ends and communicating with the spaces above and below the horizontal ⁴⁰ partition and connected together at their outer ends and a foraminated or open-work cover surrounding the drum or drums and connected to the frame and the plate.

In testimony whereof I have hereunto set ⁴⁵ my hand in presence of two subscribing witnesses.

FRANK A. DELPH.
